Paul Matthes

UNITED STATES PATENT OFFICE.

BARNEY SCHILLING, OF BROOKLYN, NEW YORK, ASSIGNOR TO THE EMPIRE TINWARE COMPANY, OF BROOKLYN, NEW YORK, A CORPORATION OF NEW YORK.

SUSPENSION MEANS FOR VESSELS.

Application filed December 1, 1922. Serial No. 604,228.

To all whom it may concern:

Be it known that I, BARNEY SCHILLING, citizen of the United States, and resident of 35 South Fifth Street, Brooklyn, in the 5 county of Kings and State of New York, have invented certain new and useful Suspension Means for Vessels, of which the following is a specification.

This invention relates to kegs, buckets or 10 vessels in general and particularly to their suspension means.

Some of the objects of my invention are to provide in such kegs or vessels for receiving liquids, suspension means which not 15 only will allow easy handling of the vessels but also reinforce their open edge while at the same time permitting an air-tight cover to be placed upon the vessels without the necessity of providing cut-outs in the cover 20 for permitting the handle to be freely operated, or for the cover to fit properly.

Another object of my invention is to so construct said suspension means as to simplify its manufacture and thereby reduce its 25 cost to a minimum.

Another object of my invention is to provide handle engaging eyes of stronger and more durable construction than heretofore manufactured.

30 Another object of my invention is to provide a novel construction of reinforcing bail suspension means where but a single wire portion extends radially from the curled or wired bead of the bail, thus necessitating only a small portion of the curled over metal to be deflected from the annular bead for permitting the wire to pass out.

The foregoing and still further objects 40 will be more fully apparent from the following description and the accompanying drawings, forming part of this specification, and in which:

Figure 1 represents a covered keg, bail or bucket in perspective view provided with my 45 suspension means.

Figure 2 is another perspective view of an open vessel illustrating the manner of attachment of my invention thereto.

Figure 3 is an enlarged partial detail view 50 of one end of my device as attached to the rim of a vessel.

Figure 4 is a partial detail cross-sectional view through a vessel equipped with my device.

Figure 5 is a perspective view of one preferred form of my device. 55

Figure 6 is a perspective view of a modified form of my device.

Referring to the drawings, numeral 10 denotes the body of a vessel, the upper open 60 end of which is provided with an annular bead 11 made in the well known manner of outwardly curling the upper edge, by so called wiring it.

Instead of using a continuous piece of 65 wire as is generally done, I insert either two semi-circular wire portions 12 and 13, as seen in detail in figure 5, or a pair of wire shapes 14 and 15, shown in Figure 6.

When using the first mentioned wire 70 shapes 12 and 13, I preferably arrange shape 12 so that one of its formed ends is positioned at the longitudinal joint 16 of the vessel while its other formed end is placed diametrically opposite, as may be seen from 75 the drawings the body portion 17 of shape 12, is semi-circular, as is the body of shape 13. The ends of shape 12 are bent radially outward from the body portion at 18 and receive semi-looped forms 19 directed with 80 their curvature downwardly. The ends of the semi-loops 19 terminate in full loops 20 disposed above the lowermost bent portion of semi-loops 19. Loops 20 form completely circular eyes and are adapted to receive the 85 looped or hook-formed ends 21 of handle 22. Its looped ends are preferably arranged at right angles to loops 20 of shape 12.

Shape 13 is plain and has no other function than reinforcing the curled bead portion of the vessel. 90

Through the formation of the loops 20 at a point somewhat removed from the body of the vessel and at the level with or above the level of the upper edge of the vessel, the suspension of the latter by handle 22 is greatly facilitated, which becomes of particular importance during the processes of carrying the filled receptacle, since the center of gravity is shifted downwardly, that is, further below the points of suspension as compared with heretofore used constructions. 95

Moreover the fact that I have ample space between loops 20 and the bead 11, a cover 23 (Figure 1) with its downturned, 100 overlapping, edge 24 may be readily pressed into airtight engagement with the bead without necessitating any portion of its edge 105

to be cut out to pass over loops 20.

Similarly the application of shapes 14 and 15 shown in Figure 6, accomplishes the desired results of keeping the center of gravity 5 of the vessel far below the points of its suspension while also permitting the airtight attachment of a cover for the vessel.

Their bodies 25 are semi-circular, one of their ends being plain, the other end having 10 the same shape as described in connection with wire form 12, and consisting of a radially outward directed portion bent at 18' and forming a downward semi-loop 19' terminating in a full loop 20' disposed above 16 the lowermost point of semi-loop 19'.

The use of the latter described construction has its advantage in that the wire shapes are both identical in form and therefore require only one bending die.

20 The fact that in both constructions the loop formation is at the ends, facilitates the manufacture and handling during the process of securing the forms within the bead of the vessel, thereby cheapening the production cost considerably.

30 A particular advantage of my construction is the fact that only a single thickness of wire issues from underneath the curled bead of the vessel edge, thus requiring but a very small portion of the bead to leave its generally tubular, reinforcing shape to be formed around the wire. In this manner a more perfect reinforcement of the vessel is assured.

35 Another important feature of my construction is the formation of a complete eye or coils 20 and 20', respectively, where handle loops 21 are to be attached providing a more secure and positive bearing for 40 the latter from which the loops can not shift to various other points thereby causing a slipping and a continuous change of

center of gravity while carrying the filled vessel.

The foregoing advantages and particularly that of effective manufacture and perfection of suspension and wear coupled with the reduced production cost will be thus fully apparent.

While having described a particular construction of my invention be it understood that changes or improvements may be made by me, without departing from the broad scope of my idea, for which I claim:

1. In a vessel suspension a semi-annular member adapted to be permanently associated with the rim of a vessel having at one end a depending semi-looped portion terminating in a full loop extending upwardly and in a radial direction from the rim of a vessel.

2. In a vessel suspension a semi-annular member adapted to be permanently associated with the rim of a vessel having at its ends depending semi-looped portions extending radially from the rim of the vessel and terminating in eyes directed upwardly and disposed above the lowermost point of the said semi-looped portions.

3. In combination with a keg, a keg suspension, comprising in part semi-annular members adapted to be permanently associated with the rim of the keg, a semi-loop provided at the ends of said members and extending radially from the keg rim, a full loop forming the end of said semi-loop and disposed above the lowermost point of the latter, a semi-circular handle having loops at right angles to said full loops of said member and adapted to engage the latter.

Signed at New York in the county of Kings and State of New York this 27 day of Nov. A. D. 1922.

BARNEY SCHILLING.
